UNITED STATES PATENT OFFICE.

JOSEPH P. NOYES, OF BINGHAMTON, NEW YORK, ASSIGNOR TO JOSEPH P. NOYES & CO., OF SAME PLACE.

DESIGN FOR A COMB.

SPECIFICATION forming part of Design No. 19,365, dated October 22, 1889.

Application filed July 9, 1889. Serial No. 316,993. Term of patent 7 years.

To all whom it may concern:

Be it known that I, JOSEPH P. NOYES, a citizen of the United States, residing at Binghamton, county of Broome, and State of New York, have invented and produced a certain new and useful Design for Combs, fully described and represented in the following specification and the accompanying illustration, forming a part of the same.

10 The distinguishing feature of the design is the shape and configuration of the end or terminal teeth of the comb. These teeth are by their shape and configuration made to represent the head and neck of an animal—such, 15 for example, as a bird or reptile. The beak or nose *a* of the animal forms the point of the

tooth, the head *b* the body or upper part of the tooth, and the neck *c* makes a graceful curve and unites with the end of the back *d* of the comb, all substantially as shown in the accompanying illustration.

What I claim is—

The design for a comb, substantially as herein shown and described.

In testimony whereof I have hereunto set my hand in the presence of two subscribing witnesses.

JOSEPH P. NOYES.

Witnesses:

W. B. EDWARDS,
WM. F. VAN CLEVE.
